UNITED STATES PATENT OFFICE.

CHARLES O. DOWST, OF WAUKEGAN, ILLINOIS.

TAG.

SPECIFICATION forming part of Letters Patent No. 401,485, dated April 16, 1889.

Application filed September 28, 1888. Serial No. 286,634. (No model.)

To all whom it may concern:

Be it known that I, CHARLES O. DOWST, a citizen of the United States, residing at Waukegan, in the county of Lake and State of Illinois, have invented a new and useful Improvement in Tags, of which the following is a specification.

My invention relates to an improved tag for use more especially in laundries and fabric-cleaning establishments generally to supply a desirable means for placing upon articles about to undergo the cleaning process the owner's name or some other designating symbol whereby to distinguish, after the cleaning process, the ownership of an article, where, as is usual, the articles of several or many owners are put through the cleaning process at one time.

My object is to provide a tag for this purpose which shall be capable of ready attachment upon the article to be cleaned, be secure in its place against detachment by the handling to which the article is subjected or the machinery through which it is passed; and, furthermore, to provide a tag having a surface capable of being written or printed upon with an indelible or moisture-proof ink, and which will not itself be injured or affected to obliterate such writing or printing by the action of moisture, and which shall at the same time be capable of repeated use and be so inexpensive that it may be discarded after a single use without entailing material loss.

To the above ends my invention consists in a tag formed of hard material, having on one surface cloth or a like material not affected by moisture in a manner to destroy it as a vehicle for characters placed thereon with ink itself ineffaceable by the action of water; and it further consists in the more detailed construction of the tag.

In the drawings, Figure 1 is a perspective view of my improved tag fastened in position upon a cloth article; Fig. 2, a plan view, enlarged, of the metal blank out of which the tag is formed; Fig. 3, a view in side elevation of the tag in its completed state; and Fig. 4, a section taken on the line 4 of Fig. 1, and viewed in the direction of the arrow.

A is the blank, comprising, preferably, a strip of thin sheet-brass or other non-corro-

sive pliant material, stamped out to or substantially to the shape shown in Fig. 2, to form a body portion, B, having edges *t* and a perforation, *s*, and the narrow extension B', provided at its extremity with fastening-points *q*.

The blank A is formed into my improved tag by bending over the edges *t* at the dotted lines *x* toward each other on the face of the body portion and bending the part B' at the line *x'* toward the back of the body portion and the points *q* at the lines *x* toward each other to extend toward the back of the body portion.

C is a strip of cloth preferably of about the length of the body portion B, and of the width of the same between the dotted lines *x*, and having, by preference, merely a perforation to coincide, when the strip of fabric is adjusted in position upon the body portion B, with the perforation *s* in the latter. The cloth, C, is placed in position upon the body portion B before the formation of the tag from the blank to cause the edges *t*, as they are bent, to clamp the edges of the fabric and hold it.

The fastening-points *q* when bent, as before described, are brought together to form practically one fastener extending toward the rear side of the part B, whereby when the part B' is bent at the line *x'* toward the part B the points of the fastener *q* will enter the perforation *s*, with which they are arranged to coincide.

I prefer in manufacturing my improved tags for the market to complete them in the form shown in Fig. 3, whereby it is only necessary in applying them to pass in each instance an edge of the article to be tagged between the point of the fastener *q* and the part B, and by pressing the fastener through said article and the perforation *s* and spreading the points apart secure the tag in position. The cloth or other material, C, affords a surface which may be readily written or printed upon with suitable ink, which will not be obliterated by the cleaning to which the tagged article is subjected, and as the tag is clamped flat against the opposite sides of the article to which it is secured and is formed of quite thin material it does not afford obstruction, and is thus not liable to be torn

from its position in cleaning the article provided with it.

Cloth is the one material at present known to me which will best answer the purpose of the part C of my improvement. I intend, however, that the use for the purpose of any textile fabric other than that generally included under the term "cloth," or any other suitable material which would be applied as a strip in the same manner as cloth, and which will absorb ink and not be injuriously affected for my purpose by moisture, shall be embraced within my invention.

What I claim as new, and desire to secure by Letters Patent, is—

1. In a tag, the combination of the body portion B, and a strip of cloth, C, on one side of the body portion and secured thereon by the bent edges t, substantially as described.

2. A tag comprising, in combination, a body portion, B, having an opening, s, a strip of cloth, C, secured on the body portion, and a bent extension, B', having a fastener, q, at one end adapted to pass through the opening s, substantially as described. 20

3. A tag comprising, in combination, a body portion, B, having an opening, s, a strip of cloth, C, on one side of the body portion and secured thereon by the bent edges t thereof, and a bent extension, B', having a fastener, q, at one end adapted to pass through the opening s, substantially as described. 25 30

CHARLES O. DOWST.
